ELECTRIC WATER HEATER

Edward L. Monnot, Canton, Ohio, assignor to
The Weber Dental Manufacturing Company,
Canton, Ohio, a corporation of Ohio

Application January 6, 1933, Serial No. 650,405

2 Claims. (Cl. 219—38)

My invention relates in general to electric water heaters which are of the type wherein walls form a storage chamber for warm water, and wherein the water is maintained at a desired temperature in the chamber, by means of a thermostatically controlled electric resistance heating element; and in particular my invention relates to electric water heaters which are adapted for use by dentists and the like for selectively supplying either warm or cold water directly to the water syringes used by dentists in connection with dental operations in the oral cavity.

Such a water heater for such dental purposes is usually supported on a dental unit or the like located closely adjacent the dental chair for convenient use by the dentist, and should be leak proof in itself, and any or all valves and fittings associated therewith should likewise be leak proof so that no water may drip or leak upon the dentist's hands during use of the heater or the water syringe with which it may be connected, and also so that there shall be no dripping or leaking of water upon the patient either while in the chair or while approaching or leaving the chair.

From another standpoint, such a dental water heater should be relatively compact so as to occupy a minimum volume of space, and thus permit free movement of the dentists about and between the chair and the unit.

From still another standpoint, such a dental water heater should be of simplified construction and arrangement permitting easy and economical assembly and disassembly during manufacturing and maintenance operations, and in which at the same time the parts are associated with each other in such manner as to provide the desired supply of warm water with a minimum consumption of current by the electric resistance heating element.

No electric water heater has been generally available which has met with complete satisfaction each and all of the above set forth desirable characteristics of electric water heaters for dental purposes.

Accordingly the objects of the present invention include the provision of an electric water heater of the foregoing general type; and which is particularly adapted for dental purposes, and which is leak proof with respect to itself and any and all of its associated valves and fittings; and which is relatively compact; and which is of simplified construction and arrangement and is easy and economically assembled and disassembled; and which includes thermal and electrical parts associated with each other in such manner as to

provide a high degree of thermal and electrical efficiency.

The foregoing and other objects are attained by the improvements, apparatus, parts, combinations, and sub-combinations, which comprise the present invention, and the nature of which is set forth in the following general statement, and preferred embodiments of which, together with their mode of use are set forth in the following description, and which are particularly and distinctly pointed out and set forth in the appended claims forming part hereof.

The nature of the improved electric water heater of the present invention may be described in general terms as including walls forming preferably an integral and compact housing, some of the housing walls preferably forming a storage chamber for water and walls forming the storage chamber preferably being provided with a lower opening, an improved closure and heat box forming member for the storage chamber opening, the closure being preferably removably seal mounted in the housing across the storage chamber opening, and the closure preferably including walls forming a downwardly opening heat box, an electric resistance heating element, preferably removably fitting within the heat box, and preferably coacting means on the heat box and heating element for releasably securing the heating element in the heat box.

Other of the housing walls preferably form a heat control chamber below the water storage chamber, and the walls forming the heat control chamber preferably being provided with a lower opening, a closure member preferably fitting and being removably secured to the housing across the heat control chamber opening, a thermostatic electric switch located in the heat control chamber, conductors operatively connecting the electric heating element and the thermostatic switch and adapted for connection with a source of electric power, whereby the temperature within the heat control chamber serves to operate the thermostatic switch so as to connect and disconnect the electric heating element with the source of electric power when the temperature within the heat control chamber falls below or arises above predetermined lower and upper temperatures within the heat control chamber, and consequently whereby the temperature of the water in the storage chamber preferably located as aforesaid above the heat control chamber may be maintained within a predetermined desired temperature range.

Others of the housing walls preferably form inlet and outlet ducts, the outer end of the inlet duct being adapted for communicating connection with a supply of water and the outer end of the outlet duct being adapted for communicating connection preferably by means of a flexible tubing with a water syringe and the like, the housing walls moreover have preferably formed therein a by-pass duct communicating directly between the inlet duct and preferably the upper end of the water storage chamber.

There is also preferably provided an inlet water directing tube, the upper end of the water directing tube preferably communicatingly connecting with the storage chamber end of the by-pass duct, and the lower end of the inlet water directing tube preferably terminating and opening preferably adjacent the closure and heat box forming member for the storage chamber opening.

The housing walls furthermore have preferably formed therein an intermediate duct having one end communicating preferably with the upper end of the water storage chamber.

There is preferably furthermore formed in the housing walls a frusto-conical rotary valve seat duct, and the other end of the intermediate duct and the inner ends of the inlet and outlet ducts communicatingly terminate adjacent each other in the valve seat duct.

The longitudinal axis of the conical valve seat duct is preferably normally vertical, and the larger end of the frusto-conical valve seat duct is preferably the lower end thereof, and a preferably removable water sealing closure is provided for the lower end of the conical valve seat duct.

A rotary frusto-conical valve stem rotatably fits and is preferably spring pressed in sealing abutment with the frusto-conical valve seat duct, and the valve stem has formed transversely therein a plurality of centrally communicatingly connecting radial ducts, and the outer ends of the radial valve stem ducts are adapted for selective connection with the ends of the inlet duct, the outlet duct, and the intermediate duct terminating in the valve seat duct, whereby, by rotation of the valve stem, the outlet duct may be entirely shut off from the water supply, or may be communicatingly connected directly either with the inlet duct for a supply of cold water; or with the intermediate duct for a supply of warm water.

The upper end of the improved rotary valve stem preferably extends above the housing beyond the upper end of the valve seat duct, and a latch controlled handle is preferably secured thereon.

The improved electric water heater furthermore includes novel detail construction and arrangement of the parts thereof as hereinafter set forth.

Preferred embodiments of the improved electric water heater and of the parts thereof are illustrated in the accompanying drawings forming part hereof, in which

Figure 1 is a fragmentary vertical sectional view as on line 1—1, Fig. 2, and with other portions broken away and illustrated in section, of an embodiment of the improved electric water heating apparatus particularly adapted for dental use, in conjunction with a water syringe not shown in Fig. 1 but shown in Fig. 6;

Fig. 2, a fragmentary vertical sectional view thereof as on line 2—2, Fig. 1;

Fig. 3, a fragmentary horizontal sectional view thereof as on line 3—3, Fig. 1, the improved valve parts of the apparatus being illustrated in their

relative closed positions, shutting off communication between the interior of the storage chamber and the outlet duct of the apparatus;

Fig. 4, a view similar to Fig. 3, in which the valve parts of the apparatus are illustrated in their relative positions simultaneously permitting the storage chamber to be maintained full of water and permitting a flow of warm water from the storage chamber into the outlet duct;

Fig. 5, a view similar to Figs. 3 and 4, and illustrating the valve parts of the apparatus in their relative positions simultaneously permitting the storage chamber to be maintained full of water and permitting a flow of cold water into the outlet duct of the apparatus;

Fig. 6, disassembled fragmentary and sectional views of certain parts of the apparatus, and a side elevation view of a form of valve controlled syringe with which the apparatus may be connected, the views of Fig. 6, being reduced in size relative to Figs. 1 to 5 inclusive;

Fig. 7, a top plan view looking in the direction of the arrows 7—7, Fig. 6;

Fig. 8, a horizontal sectional view as on line 8—8, Fig. 6;

Fig. 9, a bottom plan view of the preferred improved closure and heat box forming member, looking in the direction of the arrows 9—9, Fig. 6; and

Fig. 10, a sectional view of the electrical parts of the apparatus as on line 10—10, Fig. 6.

Similar numerals refer to similar parts throughout the drawings.

The improved electric heating apparatus is indicated generally by 10 in an embodiment particularly adapted for dental use and arranged to selectively supply warm or cold water to a dental syringe indicated generally by 11, or to entirely shut off the water supply from the syringe 11.

While the improved electric heating apparatus 10 is particularly adapted for dental use as aforesaid, it may be used when desired for heating other fluids which may be either liquids or gases.

The apparatus 10 includes walls forming preferably an integral and relatively compact housing indicated generally by 12.

Some of the housing walls indicated generally by 13 form a fluid storage chamber 14 which is preferably cylindric as illustrated, and the longitudinal axis of the cylindric chamber 14 is normally vertical in use.

The storage chamber forming walls 13 include a longitudinally extending tubular wall 13—1, and a wall 13—2 closes the normally upper end of the wall 13—1.

Intermediate the ends of the wall 13—1, the storage chamber forming walls 13 include a partition wall 13—3 which is connected at its outer periphery with the tubular wall 13—1, and which has formed therein a normally lower preferably cylindric opening 15.

In other words, as illustrated, the wall 13—3 is in the form of an annular flange wall having its outer periphery connecting with and integral with the tubular wall 13—1, and having its inner bore forming the normally lower storage chamber opening 15.

An improved combined closure and heat box forming member indicated generally by 16 is preferably removably seal mounted across the storage chamber opening 15.

A preferred form of closure and heat box forming member 16, as illustrated, includes a longitudinally extending tubular wall 16—1, whose

- diameter is substantially smaller than the diameter of the tubular wall 13—1.
- A wall 16—2 closes the normally upper end of the wall 16—1, and the smaller end of a frusto-conical wall 16—3 connects with the normally lower end of the wall 16—1, and the inner periphery of an annular sealing and mounting flange 16—4 connects with the larger and normally lower end of the frusto-conical wall 16—3.
- 10 The flange wall 13—3 of the storage chamber forming walls 13 has formed therein a plurality of internally threaded bores 17, and the sealing and mounting flange 16—4 has formed therein a plurality of apertures 18 each registering with one of the internally threaded bores 17.
- 15 A sealing gasket 19 is preferably interposed between the normally lower face of the flange wall 13—3 and the normally upper face of the sealing and mounting flange 16—4, and the closure and heat box forming member 16 is removably secured and seal mounted across the storage chamber opening 15 by means of a plurality of screws 20, the shanks of which extend each through one set of the registered apertures 18 and internally threaded bore 17 and through suitable apertures formed in the gasket 19, and the threaded inner ends of which are screwed in the bores 17 and the normally upper faces of the heads of which abut and clamp against the flange 16—4.
- 20 The tubular wall 16—1 and closure wall 16—2 of the member 16, form a longitudinally extending cylindric and normally downwardly opening heat box 21 as illustrated, and in use, the tubular wall 16 extends within the heating chamber 14 a substantial distance from the flange wall 13—3 so that the heat box end wall 16—2 is substantially midway between the storage chamber wall 13—2 and the flange wall 13—3.
- 25 30 A preferably cylindrically encased electric resistance heating element 22 preferably removably fits within the downwardly opening heat box 21, and preferably coacting means are associated with the heat box walls and with the heating element for releasably securing the heating element in the heat box.
- 35 As illustrated the releasable coacting means for securing the heating element in the heat box, include a flange ring 23 secured at the normally lower end of the heating element 22 and extending radially outwardly therefrom and having a notch 24 formed therein.
- 40 A tongue 25 extends from the inner surfaces of the frusto-conical wall 16—3 and the tongue 25 has such dimensions as to clear the notch 24 when the heating element 22 is longitudinally inserted into the heat box 21 with the notch 24 alined with the tongue 25.
- 45 After the element 22 has been inserted completely into the heat box 21, the element 22 is partially rotated so as to locate the notch 24 out of alinement with the tongue 25, whereby the tongue 25 overlaps the flange 23 and releasably secures the heating element 22 within the heat box 21.
- 50 The tubular wall 13—1 includes a normally lower end portion 13—1' which extends beyond the normally lower faces of the closure member 16, and forms with the closure member 16 a heat control chamber 26 having a normally lower opening 27, and a closure member 28 preferably fits across the opening 27 and is secured to the wall portion 13—1', as by means of screws 29 whose shanks pass through suitable apertures in the closure member 28 and which have threaded
- 55 inner ends screwed into suitable internally threaded bores 30 formed in the wall portions 13—1' and the external heads of the screws 29 clamping the closure member 28 against the wall portions 13—1 in the usual manner.
- 60 A thermostatic electric switch indicated generally by 31 is located within the heat control chamber 26 and is preferably removably secured below the normally lower faces of the frusto-conical mounting wall 16—3, as by means of screws 32 whose threaded shanks are screwed into suitable internally threaded bores 33 formed in the frusto-conical wall 16—3, and the heads of which screws 32 overlap a mounting plate 34 of the thermostatic switch 31.
- 65 The electric heating element 22 and the thermostatic switch 31 are of usual construction, and conductors indicated generally by 35 operatively connect the electric heating element and the thermostatic switch in a usual manner and are adapted for connection with a source of electric power, not shown, whereby the temperature within the heat control chamber 26 serves to operate the thermostatic switch 31 so as to connect and disconnect the electric heating element with the source of electric power when the temperature within the heat control chamber 26 falls below or arises above predetermined lower and upper temperatures, and consequently whereby the temperature of any liquid such as the usual water in the storage chamber 14, which is preferably located as aforesaid above the heat control chamber 26, may be maintained within a predetermined desired temperature range.
- 70 The foregoing construction and arrangement of the closure and heat box forming member 16 with respect to the storage chamber 14, with respect to the electric resistance heating element 22 and the thermostatic switch 31, and with respect to the heat control chamber 26, serves to attain a high degree of electrical and thermal efficiency for the improved heating apparatus 10.
- 75 The housing 12 also includes other walls indicated generally by 36 which have formed therein a novel arrangement of inlet, outlet, and by-pass ducts or openings for the storage chamber, as hereinafter set forth in detail, and the walls 36 also form part of and operatively mount a rotary selector valve indicated generally by 37 which is associated with the several ducts formed in the walls 36.
- 80 As aforesaid, the walls 36 are preferably integral with the other walls of the housing 12, and are preferably located at the normally upper end and at one side of the tubular wall 13—1.
- 85 The several ducts formed in the walls 36 include an inlet duct 38, the outer end of which is adapted for communicating connection as by means of a coupling 39 with a supply of water or other fluid, not shown, and the water or fluid having a gravity, and/or pressure, and/or velocity head, whereby the storage chamber 14 is maintained full of water or other fluid at all times.
- 90 The ducts formed in the walls 36 also include an outlet duct 40, the outer end of which is adapted for communicating connection as by means of a coupling 41 with one end of a flexible tubing 42, and the other end of the tubing 42 communicating connects with the valve controlled syringe 11.
- 95 The ducts formed in the walls 36 also include a by-pass duct 43 communicating directly between the inlet duct 38 and the upper end of the water storage chamber 14.

An inlet water directing tube 44 is preferably provided and the upper end of the tube 44 connects with the end of the by-pass duct 43 in the storage chamber 14, and the lower end of the tube 44 preferably terminates and opens adjacent the closure and heat box forming member 16, whereby the cold inlet water is directed to the warmest part of the storage chamber 14 adjacent the member 16 which mounts as aforesaid the heating element 22.

10 The housing walls 36 preferably furthermore have formed therein an intermediate duct 45 having one end communicating preferably with the upper end of the storage chamber 14.

15 The housing walls 36 also have preferably formed therein a preferably frusto-conical rotary valve seat duct 46 extending angularly with respect to all of the other ducts formed in the walls 36, and the other end of the intermediate 20 duct 45 and the inner ends of the inlet duct 38 and the outlet duct 40 communicatingly terminate adjacent each other in the valve seat duct 46.

25 The longitudinal axis of the conical valve seat duct is preferably normally vertical, and the larger end 47 of the frusto-conical valve seat duct is preferably the lower end thereof, and a preferably removable water sealing externally threaded closure 48 is provided for the internally threaded lower end of the duct 46.

30 A rotary frusto-conical valve stem 49 rotatably fits and is preferably spring pressed in sealing abutment with the frusto-conical valve seat duct 46, as by means of a compression spring 50 interposed between the normally lower larger end 35 of the valve stem 49 and the normally upper and inner face of the closure 48.

35 The valve stem 49 has formed transversely therein, a plurality of centrally communicating radial ducts 51, 52, and 53, and the other ends 40 of the ducts 51, 52, and 53 are adapted for selective connection with the ends of the inlet duct 38, the outlet duct 40, and the intermediate duct 45 terminating in the valve seat duct 46, whereby, by rotation of the valve stem 49, the 45 outlet duct may be entirely shut off from the water supply and from the storage chamber as illustrated in Fig. 3, or may be communicatingly connected directly with the intermediate duct for a supply of warm water as indicated in Fig. 4, 50 or may be communicatingly connected directly with the inlet duct for a supply of cold water, as illustrated in Fig. 5.

55 The upper end of the valve stem 49 extends above the housing 12, and beyond the normally upper end of the valve seat duct 46, and an op-

erating handle 54 is secured upon the upper end of the stem 49, and latch means indicated generally by 55 are interposed between the handle 54 and the upper end of the walls 36, whereby the valve stem 49 is releasably maintained in either one of its three selective positions, after manual rotation to any of said positions.

I claim:

1. Valve apparatus including walls having formed therein a plurality of ducts, the ducts including an inlet duct having one end adapted for communicating connection with a source of fluid and the like, an outlet duct having one end adapted for communicating connection with a valve controlled syringe and the like, an intermediate duct having one end adapted for communication with the interior of a storage chamber and the like, a valve seat duct, and the other ends of the inlet, outlet, and intermediate ducts communicatingly terminating in the valve seat duct, a valve stem rotatably fitting in the valve seat duct and the valve stem having formed transversely therein a plurality of centrally communicatingly connecting radial ducts, and the outer ends of the radial valve stem ducts being spaced for selective connection some with the valve duct ends of the inlet duct and the outlet duct and some with the valve duct ends of the intermediate duct and the outlet duct.

2. Apparatus for heating fluid and the like, including walls forming a storage chamber for the fluid, some of the walls having formed therein a plurality of ducts, the ducts including an inlet duct having one end adapted for communicating connection with a source of the fluid, an outlet duct having one end adapted for communicating connection with a valve controlled syringe and the like, a by-pass duct communicatingly connecting the inlet duct with the interior of the storage chamber, an intermediate duct having one end communicating with the interior of the storage chamber, a valve seat duct, and the other ends of the inlet, outlet, and intermediate ducts communicatingly terminating in the valve seat duct, a valve stem rotatably fitting in the valve seat duct and the valve stem having formed transversely therein a plurality of centrally communicatingly connecting radial ducts, and the outer ends of the radial valve stem ducts being spaced for selective connection some with the valve duct ends of the inlet duct and the outlet duct and some with the valve duct ends of the intermediate duct and the outlet duct, and means for heating some of the walls of the storage chamber.

EDWARD L. MONNOT.
